UNITED STATES PATENT OFFICE

HYACINTH O. COOK, OF PHILADELPHIA, PENNSYLVANIA

FOLDING SWEATER STRETCHER

Application filed November 1, 1930. Serial No. 492,824.

My present invention has reference to a garment stretcher, and more particularly to a device for stretching sweaters and like woolen garments to prevent the shrinkage thereof after the garment has been washed or otherwise cleaned with a fluid.

A further object of the invention is the provision of a stretcher for use in drying and preventing the shrinkage of sweaters or like woolen garments which shall be both of an adjustable and collapsible construction whereby the stretcher may be employed upon various sizes of garments and also whereby the stretcher, when not in use, can be folded into a small package.

A further object is the provision of a device for this purpose that is characterized by simplicity in construction, cheapness in manufacture and thorough efficiency in practical use.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a front elevation of my improved stretcher for use in drying and preventing the shrinkage of garments.

Figure 2 is a rear elevation thereof.

Figure 3 is a view showing certain of the elements constituting the improvement separated and the remaining elements partly folded.

Figure 4 is a sectional view approximately on the line 4-4 of Figure 1.

Figure 5 is a sectional view approximately on the line 5-5 of Figure 1.

Figure 6 is a front elevation of a slight modification.

Figure 7 is a rear elevation thereof.

Figure 8 is an enlarged plan view of the bottom plate of the improvement.

Figure 9 is a sectional view approximately on the line 9-9 of Figure 8.

Figure 10 is a sectional view approximately on the line 10-10 of Figure 8.

Figures 11, 12, and 13 illustrate different sized spacer blocks which may be employed.

Figure 14 is an elevation of a further slight modification.

Figure 15 is a similar view of a still further modification.

Figure 16 is a view to illustrate an ordinary nut which may be employed.

The improvement may be constructed of either wood or metal and in each instance the elements comprising the improvement are comparatively thin strips or plates. In all of the forms of the improvement the stretcher includes a top strip or plate 1, side strips or plates 2, a bottom strip or plate 3, which is of a greater width than the strips 1 and 2 and forked strips or plates 4 that comprise the substantially V-shaped arms of the frame. The top member 1 has its edges, at points equidistant from its center, inclined in opposite directions to provide rests for the shouldered portions of the sweater 5. The arms 4 have their outer ends connected, the said connecting portion being of a greater width than that of the spaced angularly disposed elements that constitute the forked arms and this end of the fork is for distinction indicated by the numeral 6. The sleeves of the garment are arranged over the angle arms 4 and the wrist bands thereof arranged over the reduced outer ends 6 of the arms 4. Arranged on the opposite faces of the ends 6 of the arms there are clamping plates 7 movable toward or away from each other by adjustable means broadly indicated by the numeral 8. The adjustable means is preferably in the nature of a bolt engaged by either a wing or an ordinary nut and the clamping plates 7, binding upon the cuffs of the sleeves will hold the said sleeves of the garment in proper position on the arms of the frame.

The body of the garment is contacted by the outer edges of the side members 2 of the stretcher frame, and as dis-

closed by certain figures of the drawings the lower edges of the said side members may be arranged at inward angles, indicated by the numeral 9 and connected to the bottom plate 3 and the lower edges of the garments will follow the contour of the outer edges of the side members of the frame. The bottom of the garment is received between clamping plates 10. The clamping plates are arranged upon the opposite sides and in a line with the outer edge of the bottom plate or strip 3. The clamping plates are secured to the strip 3 in a particular and peculiar manner. The clamping plates are provided, at suitable points, with spaced notches 11 that receive therein the heads of bolts 12 that pass through the bottom strip 3 and through the cooperating clamping plate, the outer ends of the said bolts being engaged by either wing nuts or ordinary nuts as disclosed by Figure 16 of the drawings. The notches of the respective plates are arranged out of alignment with each other so that the bolts 12 are arranged in the opposite sides of the frame. In addition to the bolts 12 outer bolts 13 are passed through the member 3 and through the clamping plates adjacent to the outer ends thereof. These bolts are, of course, engaged by either wing or ordinary nuts.

In order to provide for the collapsing of the frame one end 9 of the side members 2 is connected to the bottom strip or plate 3 by adjustable means in the nature of bolts 14 which are engaged by suitable wing or like nuts 15. The bolts are inserted in the opposite sides of the frame. The opposite end 9 is connected to the bottom strip by a rivet 9'.

The side members 2 are each preferably constructed of two members held together by pivot bolts 16 which, of course, are engaged by nuts. In a like manner the bifurcated or forked elements of the arms 4 are connected to the sides 2 by bolts and nuts. The inner corners of the side members 2 are notched to receive the said bolts therethrough. Also the outer corners of the top 1 are notched so that bolts, engaged by nuts, may pass through the upper and longer elements of the forked or bifurcated arms 4 and through the upper corners of the top strip or plate 1. Rivets 18 pass through the lower end portions of the top members and through the sides 2, while a hanger hook 19 is passed through the top 1. By a construction as above described it will be apparent that the frame constituting the structure may be readily assembled to receive a garment thereover, to effectively clamp the garment on the stretcher frame, and to permit of the drying without allowing the shrinkage of the garment. It will also be apparent that the elements constituting the device may be supported from each other or swung upon each other, as disclosed by

Figure 3 of the drawings and thereby provide a small package for storage when the structure is not required for use.

In Figures 6 and 7 the construction slightly differs. In these views the upper strip or member of the frame comprises two lapping sections, one or both being provided with a series of apertures 20 through certain of which pass adjustable securing means in the nature of bolts which are engaged by nuts 21. The series of apertures 20 are preferably disposed adjacent to the top and the bottom of the upper strip of the frame, and the upper strip carries a plurality of hooks 22, one of which will be arranged in a line with the center of the frame when the said frame is adjusted. The upper elements of the bifurcated or forked arms of the improvements are connected to the corners and to the sides of the frame in a manner as previously described. The forked elements constituting the arms, in this instance, however, comprise lapping sections provided with a series of apertures through one pair of which there are passed bolts 23 which are engaged by suitable nuts and whereby the arms are adjusted with respect to the body of the frame. The outer ends of the arms carry clamps as heretofore described. The side members of the frame also comprise lapping sections provided with series of apertures 24 designed to align and through at least one pair of each series of apertures there are passed bolts 25 engaged by suitable nuts.

The lower members comprising the arms are pivotally secured, as at 23', to the outer widened ends of the upper arms, and the inner sections of the lower arms have their removable pivots passing through one of a series of apertures 26' in the side members of the frame, and whereby the arms, at the ends thereof may be spread away from each other and adjustably secured to the side members of the frame. This provides for the stretching of sweaters having different size sleeves and different widths of sleeves at the juncture with the body of the said sweater.

The bottom strip comprises two members which are arranged in lapping relation but these lapping portions are reduced from their opposite faces, is at 26, to approximately one-half of the thickness of the said bottom strip. One of the lapping portions 26 is provided with a series of apertures 27 through one of which there is passed a bolt 28 that passes through a single opening in the second lapping portion of the bottom strip. The bolt is, of course, engaged by a nut 29. When the sections comprising the bottom strip are moved a distance outwardly with respect to each other there is arranged within the space or gap thus provided one of a plurality of different width spacer strips 30, such as is disclosed by Figures 11 and 13 of the drawings and likewise disclosed by Figures 8 and 9 of

the drawings. These strips have their lower ends provided with apertures 31 and through these apertures and through one of a series of openings in the bottom plate or strip there are passed bolts 32 that also pass through the apertures 31 in the spacer strips 30. Through certain of the remaining apertures in the bottom plate or strip there are passed bolts 33 that are also passed through one of a series of apertures in the clamping plates 34.

10 The heads of the bolts 32 are received in notches 35 in the clamping plates 34, as disclosed by the drawings.

15 In Figure 14 the construction is substantially similar to that described in connection with Figures 1 to 5 of the drawings, except that the side strips 1' of the frame are straight throughout their length, while in Figure 15 the frame provided with straight side strips 20 1" is connected to an adjustable bottom plate or strip similar to that disclosed in connection with Figures 6, 7, 8, 9 and 10 of the drawings, the adjustable strip having secured thereto clamps similar to the clamping plates 25 34 described in connection with the foregoing figures.

By constructing the frame of adjustable as well as removable and collapsible members it will be apparent that sweaters of various sizes may be successfully stretched, dried and prevented from shrinkage, it being understood that the sweaters or like garments are arranged upon the frames when in wet condition. The construction, it will be noted, is 35 comparatively simple, may be readily set up and adjusted to have a sweater arranged thereon. A structure in accordance with this invention is highly desirable as from experience I have found that woolen sweaters 40 shrink several sizes smaller after being washed in water, gasoline or other fluids with the result that the same, when cleaned, cannot be again employed and as a result the sweaters are discarded which results in loss of money. With my improvement the owner 45 may possess himself of several sweaters, so that he may wear one while another is being dried and stretched without permitting of the shrinkage thereof on the improvement, and it is believed the construction and advantages 50 of my device will be understood and appreciated by those skilled in the art to which such invention relates so that further detailed description will not be required.

55 Having described the invention, I claim:

A sweater stretcher comprising a frame including a top strip carrying a hook, side strips having inwardly disposed lower end portions, a bottom strip attachable with said inwardly disposed end portions and substantially V-shaped arms secured to the corners of the frame at the ends of the top and side strips, all of said strips being pivotally connected together and certain of the pivots being removable, said strips constituting adjustably con-

nected sections, clamping plates carried at the opposite sides of the lower strip and other clamping plates carried at the outer ends of the V-shaped arms.

In testimony whereof I affix my signature. 70

HYACINTH O. COOK.
